ABSTRACT

A high pressure pump is provided for independent variable control of the rate of flow in the different flows which are supplied by the pump. A plurality of fluidhandling working chambers of substantially radially expanding and contracting volume are provided in the rotor of the pump for delivery of high pressure fluid out of the pump; separated passage means are associated to the different working chamber groups; the working chamber groups are separated from each other for preventing flow from one flow into the other and separated actuator means and separated control-means associated to the separated actuator means are provided in the pump for the capability of independent variability of the rate of flows through the pump; while the whole device is constructed in such a way, that high pressure fluid can be handled in the pump and that high differences in pressure in the different flows are possible and managed and handled in the double flow pump.

INDEPENDENT VARIABLE MULTIFLOW HIGH PRESSURE PUMP

CROSS REFERENCE TO RELATED APPLICATIONS

This application is a division of my copending patent application Ser. No. 2,624, filed Jan. 13, 1970, which application Ser. No. 2,624, in turn, is a continuation-in-part of my patent application Ser. No. 749,028, filed on July 31, 1968, which application Ser. No. 749,028, in turn, is a continuation-in-part of my patent application Ser. No. 461,483, filed June 4, 1965, now U.S. Pat. No. 3,398,698.

REFERENCE TO ANOTHER PATENT This patent application deals with the matter of FIGS. 25 to 27 of my U.S. Pat. No. 3,398,698 issued on Aug. 27, 1968. It contains FIGS. 25 to 27 of said patent as FIGS. 1 to 3 in the present patent application.

THIS INVENTION

As far as multiple flow pumps have been utilized in the past they have either been non-variable or they have been of less efficiency, high volumetric losses or of low pressures in fluid only. Because the fluidhandling chambers were not tightly enough sealed or the actuator means or the displacement means were not rigid enough to exercise high displacement force. In other devices the fluidhandling means deformed under high pressures in fluid and restricted the pressures in the fluid in the device. Such known devices have successfully operated at low pressures or at equal rates of flow and at equal pressures in the different flows but they were not able to handle different pressures and different rates of flow in pressure — and rate of flow — independent varied machines or vehicles. On the other hand for machines and vehicles with horizontal and vertical movements it is necessary to utilize different pressures and different rates of flow during operation of the device. At the same time the horizontal movements and the vertical movements should be driven by the same power plant in order to make the control of the maximum of output depending on the power plant.

It is therefore the aim of this invention to provide an independent variable multiflow-multipressure pump, wherein the rate of flow and the pressure of the different independent flows can be controlled, varified and increased to high pressures.

It is therefore the object of this invention to provide a plurality of substantially radially enlarging and contracting fluid handling chambers capable of handling high pressures in fluid tightly arranged in two different working chamber groups in a single rotor of a fluidhandling device; to keep the said working chamber groups of the one working chamber group separated and sealed off from the working chambers of the other working chamber group and to provide each an independently variable control device or adjustment device for adjustment of the displacement stroke of the displacement members which are associated to the respective working chambers of the respective working chamber group. The adjustment device associated to the one working chamber group is independently variable of the adjustment device of the other working chamber group.

Another object of the invention is, to provide the adjustment devices radially of the same rotor in order to make a strong adjustment also against high pressures possible.

5 A further object of the invention is to provide the self-adjustment members onto the adjustment devices in order to prevent tilting and friction between actuator means and adjustment control devices.

10 A further object of the invention is, to bear the rotor of a multiple flow multiple pressure pump in the same bearings for containing the different rates of flow and the different pressures in the fluid handling chambers in the same revolving rotor.

15 And it is another object of the invention to combine the adjustment devices of a multiple adjustable multiflow pump with flow direction control valves.

20 A last object of the invention is, to lead the different flows of fluid axially into and out of the same rotor in order to prevent radial deformation or friction on radial control bodies in earlier machines of different adjustable pressures and flows.

REFERENCE TO THE DRAWINGS

Some typical embodiments of the invention are demonstrated in the drawings.

25 FIG. 1 is a longitudinal sectional view through an embodiment of the invention;

30 FIG. 2 is a cross-sectional view through FIG. 1 taken along the line II — II; and

35 FIG. 3 is a longitudinal sectional view through another embodiment of the invention.

BRIEF DESCRIPTION OF THE DRAWINGS

The invention is more in detail described in the brief description of the figures of the drawings which follows below.

40 More details and features or objects of the invention may become apparent from the study of the brief description of the drawings.

45 In the embodiment of FIGS. 1 and 2 a fluid machine has the feature that there are two working chamber groups 2 and 3 provided in this embodiment of the invention and that in each of these working chamber groups a plurality of working chambers are provided wherein a plurality of displacement means are moving inwards and outwards, each displacement means group in the respective working chamber group and wherein two separated adjustment devices and two separated actuator means are provided in order to make the displacement adjustment of each of the displacement devices possible. This feature provides the possibility that at least two separate flows of fluid can flow through the machine and that each flow of fluid which flows through this machine can be varied in its flow rate separately from the other and independently from the other by adjusting the displacement adjustment devices of the respective displacement groups.

50 In the left side of FIG. 1 there is inside of the respective rotor means 1 the first working chamber group 2 provided which has a plurality of working chambers 2. 55 From each of the working chambers at least one respective rotor passage 14 extends in one axial direction through rotor means 1 and through the rotary control face on the axial end thereof. It cooperates with stationary control face on the respective control part or control portion or body of the housing 10 which has end members 10a, 10b.

Fluid ports 14 and 15 are provided in the control portion of housing 10 and they are passing fluid to and from the respective rotor passage 14. The working chambers 2 of this working chamber group are provided with displacement means 4 therein and displacement means 4 are moveable inwards and outwards in the working chambers thereby increasing and decreasing periodically the volume of the respective working chamber. Displacement means 2 are in this embodiment shown as a preferred type of pistons which have piston shoes 5 and the piston shoes 5 are having outer faces which are abut inner faces of a bearing 12. The bearing 12 which is a guide member is located in another radial flexible or divided bearing means 11 which has an inner face which corresponds complementary to the spherical outer face of the bearing 12. Bearing means 11 has an outer face which is preferably cylindrical and which is fixed in an inner face of the rotary guide means or rotary guide means 8 and 9. Bearing means 11 is axially moveable within the hollow rotary guide member 8. Rotary guide member 8 is borne in radial anti-friction bearings 7, preferably in a plurality of such bearings, which are axially spaced from each other by a spacer ring means provided between the two respective bearings 7. Bearings 7 are borne in the moveable adjusting device 19 and mount annular projecting portions 8a and 9a of guide means 8 and 9. Adjustment device 19 may be provided or is in this embodiment preferably provided with an adjustment connection means 21 and the actuation of the connection means 21 therefore leads to radial movements of adjustment device 19 and thereby radial movement of all parts which are borne therein including the actuator means. Therefore if the rotor of the machine revolves and if no eccentricity is present between the axis of the rotor and the axis of the adjustment device 19 then the inward and outward movement of the displacement means 4 in the working chambers 2 terminates. Rotor means 1 may have rotor shaft portions which may have outer faces 6 and which may be rotatably borne in respective bearings or inner faces of respective housing portions or cover means.

Rotor means 1 may also extend in a shaft means 13 whereby it may be driven or whereby the rotor drives another machine part. On the other axial portion of the rotor means 1 is the other working chamber group 3 provided which also contains a plurality of working chambers 3 wherein also displacement means 4 are moving radially outward and inward when the rotor 1 of the machine revolves. The operation of thus displacement means 4 is similar to that of the other displacement means group but the ring 11 is located in the rotary guide member 9 instead of in the rotary guide member 8 wherein the other ring 11 of the other working chamber groups or displacement means groups was located. From each of the working chambers 3 in the working chamber group 3 of rotor means 1 a respective rotor passage 14 extends in the other axial direction through rotor means 3 and through the rotary control face on the respective end of the rotor means 1 for co-operation with the respective stationary control face on the portion of the housing 10 or cover means 1. Rotary guide member 9 is again borne in radial anti-friction bearings 7 and bearings 8 are borne in the second adjustment device 20. Second adjustment device 20 has an adjustment device communication means 22. If the communication means 22 is actuated then the adjust-

ment device 20 moves radially to the axis of the rotor and if an eccentricity is present between the axis of the adjustment device 20 and the axis of rotor means 1, when rotor means 1 revolves then respective inward and outward movement of the respective displacement means 4 in the respective working chambers 3 terminates and a flow of fluid is flowing therethrough. Therefore according to this embodiment of the invention two flows of fluid are flowing through the machine or are actuated in the machine and both flows of fluid can be varied in its quantity independently from each other by the independent fluid flow adjustment control devices or displacement adjustment control devices 19 or 20 with communication or connection members 21 or 22.

From the rotor passages 14 on the right side of rotor 1 there are extending respective control ports and fluid passages to respective fluid ports 16 and 17 of the housing 10.

A special feature of this embodiment of the invention is that both flows are variable and that both flows are reversible and that both flows can be independently varied by separate fluid flow quantity adjustment devices. A further feature is that the rotor means 11 is axial pressure balanced by pressure acting out of fluid in respective chambers. A further feature is that the piston means 4 and the guide shoes 5 thereon are prevented from any tilting and sticking to the guide means because the guide means are spherically swingable. The guide members 12 are self-adjusting in order to have axes which are exactly parallel to the axes of the piston shoes 5 of the pistons 4. Therefore between these respective members any tilting is prevented. The supply of such a spherical adjustment means and axially moveable adjustment means is very important since the rotary guide members 8 and 9 of this embodiment of the invention are borne in bearings which are provided in one axial end thereof only. Such bearings might therefore during a longer life of the machine get different radial clearances and therefore the axes of the rotary guide members 8 and 9 may during a longer life or operation of the machine tend to tilt or incline a little with respect to the rotor axis. That would then in turn result of inclination between the outer faces of the piston shoes and the inner faces of the guide members if no adjustable bearings and axially moveable rotary members 12 and 11 would be provided. By the provision of the several means a perfect fluid handling device for two flows of variable and reversible fluid flow is assured and created by this embodiment of the invention.

In FIG. 3 there is another embodiment of the invention demonstrated which also shows a two flow fluid handling device. There are two working chamber groups 102 and 103 provided in the rotor means 101 of this embodiment of the invention and both working chamber groups are actuating or actuated each one of separated flow of fluid. Check valve means 25 are provided for the entrance of fluid into the respective working chambers while exit check valve means 26 are provided after each working chamber in order to open or close the respective passages to or from the respective working chambers. Separate fluid passages 27 and 28 are provided in order to pass two separated flows of fluid out of the rotor means 101 of the machine. An axially extending portion is provided on rotor means 101 wherethrough the respective fluid passages 27 and 28

extend and this portion revolves in a bearing portion of the housing 110 of the machine. The rotor means 101 with its shaft 113 is borne in respective bearing means 106 which makes a revolution of the rotor means possible. The actuator means include first and second actuator guide means 108, 109 with annular axially projecting portions 108a, 109a similar to 8, 9, 8a, 9a in the embodiment of FIGS. 1, 2. The use of a check valve in the inlet means and outlet means to the fluid chambers assures that no leakage through control interfaces or through stationary and rotary control faces will happen. The disadvantage thereof is on the contrary that such a fluid machine as shown in FIG. 3 can only act as a fluid pump or as a compressor and that it can deliver flows only in one delivery direction. Therefore according to this invention directional control means or control cylinders 34, 35 with control pistons 32 therein are provided for the directional control of the respective delivered flows. One flow of fluid is delivered through passage 27 while the other is delivered to passage 28 and one of the flows is controlled directly or indirectly by control means 34 while the other is controlled by control means 35 inner control slides 39, 40 are provided in control pistons 32.

The control pistons of the directional control valves 34 and 35 have connection means for the connection of the respective fluid flow adjustment devices 121 or 122 with the respective directional control piston 32. A gearing means or transmission means may be provided between the respective directional control pistons 32 and the respective fluid flow adjustment device 121 or 122 so that an axial movement of the control piston 32 out of its central neutral position results in a displacement increase in the respective working chambers while the displacement of the respective displacement means is zero if the control piston of the directional control valve 32 is moved into its neutral position. For this purpose the transmission means are provided between a respective control piston 32 of a respective directional control valve 34 or 35 and a respective fluid flow adjustment device 121 or 122. It may for instance be a cam with a slot means cam slot 33 in piston 32 and a respective connection follower pin or the like may be provided in slot 33 secured to the respective fluid flow adjustment device 121 or 122.

What is claimed, is:

1. In a fluid handling device, in combination, a housing means having bearing means, first and second end members, first inlet and outlet means, and second inlet and outlet means, respectively; rotor means including a rotor and a rotor shaft mounted in said bearing means for rotation about an axis, said rotor having two axially spaced first and second groups of circumferentially spaced radial working chambers, and first and second groups of circumferentially spaced passages communicating with said first and second groups of working chambers, respectively, and with said first and second inlet and outlet means, respectively, during rotation of said rotor means, said rotor means including means for fluid tightly separating said first groups of working chambers and passages from said second groups of working chambers and passages; first and second groups of displacement means mounted in said working chambers, respectively for radial movement; rotary first and second annular actuator guide means including first and second annular portions surrounding said first and second groups of displacement means, respec-

tively, and having first and second inner annular surfaces, first and second bearing and self-adjusting rings having planar faces and part-spherical faces and located between said first and second displacement means and said first and second inner annular surfaces of said first and second annular portions of said first and second annular actuator guide means; and first and second adjusting means mounted in said housing means inward of said first and second end members, and including first and second support portions movable in radial direction, first and second adjusting rings secured to said first and second support portions, respectively, and surrounding said first and second annular portions, respectively, and first and second bearings between said first and second adjusting rings and said first and second annular portions so that the eccentricity of said first and second annular actuator guide means relative to said axis can be independently adjusted by said first and second adjusting means whereby the flow rate of first and second streams flowing through said first inlet and outlet means and said second inlet and outlet means can be independently adjusted.

2. In a fluid handling device, in combination, a housing means having bearing means, first and second end members, first inlet and outlet means, and second inlet and outlet means, respectively; rotor means including a rotor and a rotor shaft mounted in said bearing means for rotation about an axis, said rotor having two axially spaced first and second groups of circumferentially spaced radial working chambers, and first and second groups of circumferentially spaced passages communicating with said first and second groups of working chambers, respectively, and with said first and second inlet and outlet means, respectively, during rotation of said rotor means; first and second check valve means in said first and second passages, respectively, for permitting flow only in one flow direction; said rotor means including means for fluid tightly separating said first groups of working chambers and passages from said second groups of working chambers and passages; first and second groups of displacement means mounted in said working chambers of said first and second groups of working chambers, respectively, for radial movement; rotary first and second annular actuator guide means including first and second annular portions surrounding said first and second groups of displacement means, respectively, and having first and second inner annular surfaces engaged by said first and second groups of displacement means, respectively, and first and second annular projecting portions projecting outward in axial direction toward said first and second end members, respectively; first and second adjusting means mounted in said housing means inward of said first and second end members, and including first and second support portions movable in radial direction, first and second adjusting rings secured to said first and second support portions, respectively, and surrounding said first and second annular portions, respectively, and first and second bearings between said first and second adjusting rings and said first and second annular portions; and first and second control valve means having first and second slides connected with said first and second adjusting means for independently adjusting the flows through said first and second inlet and outlet means so that the eccentricity of said first and second annular actuator guide means relative to said axis can be independently adjusted by said first

and second adjusting means whereby the flow rate of first and second streams flowing through said first inlet and outlet means and said second inlet and outlet means can be independently adjusted.

3. In a fluid handling device, in combination, a housing means having bearing means, first and second end members, first inlet and outlet means, and second inlet and outlet means, respectively; rotor means including a rotor and a rotor shaft mounted in said bearing means for rotation about an axis, said rotor having two axially spaced first and second groups of circumferentially spaced radial working chambers, and first and second groups of circumferentially spaced passages communicating with said first and second groups of working chambers, respectively, and with said first and second inlet and outlet means, respectively, during rotation of said rotor means, said rotor means including means for fluid tightly separating said first groups of working chambers and passages; first and second groups of axially spaced displacement means mounted in said working chambers of said first and second groups of working chambers, respectively, for radial movement independently of each other; rotary first and second axially spaced annular actuator guide means mounted in said housing means for radial movements independently of each other, and including first and second axially spaced annular portions surrounding said first and second groups of displacement means, respectively, and having first and second inner annular surfaces engaged by said first and second groups of displacement means, respectively, and first and second axially spaced annular projecting portions projecting outward in axial direction toward said first and second end members, respectively; first and second axially spaced adjusting means mounted in said housing means inward of said first and second end members, and including first and

second axially spaced support portions movable in radial direction independently of each other, first and second axially spaced adjusting rings secured to said first and second support portions, respectively, and surrounding said first and second annular projecting portions, respectively, and first and second bearings between said first and second adjusting rings and said first and second annular projecting portions so that the eccentricity of said first and second annular actuator guide means relative to said axis can be independently adjusted by said first and second adjusting means whereby the flow rate of first and second streams flowing through said first inlet and outlet means and said second inlet and outlet means can be independently adjusted; and valve means for controlling the flow into said inlet means and out of said outlet means, and including two axially movable valve slide means connected with said first and second adjusting means respectively.

20 4. A device as claimed in claim 3 wherein said first and second groups of working chambers are formed in an integral rotor body.

25 5. A device as claimed in claim 3 wherein said passages have substantially radial portions connected with said working chambers.

30 6. A device as claimed in claim 3, wherein said annular portions surrounding said first and second groups of displacement means having a greater diameter than the diameter of said annular projecting portions of said first and second annular guide means and of said adjusting rings.

35 7. A device as claimed in claim 6 wherein said first and second bearings are first and second anti-friction bearings.
